CLAIM

The ornamental design for an instrument cart element, as shown and described.

DESCRIPTION

FIG. 1 is a top, front, left perspective view of an instrument cart element;

FIG. 2 is an enlarged view of a portion of FIG. 1;

FIG. 3 is a front view of the instrument cart element;

FIG. 4 is an enlarged view of a portion of FIG. 3;

FIG. 5 is a rear view of the instrument cart element;

FIG. 6 is a right-side view of the instrument cart element;

FIG. 7 is a left-side view of the instrument cart element;

FIG. 8 is a top view of the instrument cart element; and,

FIG. 9 is a bottom view of the instrument cart element.

In the drawings, the broken lines illustrate portions of the instrument cart that form no part of the claimed design.
